UNITED STATES PATENT OFFICE.

PERCIVAL H. TRUMAN, OF EVANSTON, ILLINOIS, ASSIGNOR TO WALTER P. MURPHY,
OF CHICAGO, ILLINOIS.

END STRUCTURE FOR RAILWAY-CARS.

1,206,175.

Specification of Letters Patent.

Patented Nov. 28, 1916.

Application filed March 23, 1914. Serial No. 826,738.

To all whom it may concern:

Be it known that I, PERCIVAL H. TRUMAN, a citizen of the United States, residing at Evanston, in the county of Cook and State 5 of Illinois, have invented certain new and useful Improvements in End Structures for Railway-Cars, of which the following is a specification.

My invention relates to sheet steel end 10 structures for railway cars particularly suitable for box freight cars. The regulations of the Interstate Commerce Commission require certain clearance between the portions of the ends of a box car where the end ladders are placed, the object being to insure 15 the safety of trainmen using the ladders. This requirement does not apply to the center portion of the end of the car which may be made to bulge or project beyond the portions at the sides of the car.

The primary object of my invention is to 20 provide a car end structure which takes advantage of the fact that the center portion of the end may project out beyond the side 25 portions and utilizes this space at the center of the car for giving added strength and rigidity to the end structure without diminishing the loading capacity of the car.

The invention has for further objects such 30 other new and improved constructions, arrangements and devices in sheet metal car ends as will be hereinafter described and claimed.

The invention is illustrated, in certain 35 preferred embodiments, in the accompanying drawings, wherein—

Figure 1 shows, in elevation, a sheet metal car end, of one type, constructed in accordance with my invention. Fig. 2 is a vertical 40 sectional view taken on line 2—2 of Fig. 1. Fig. 3 is a sectional plan on line 3—3 of Fig. 1. Fig. 4 is a view, in perspective, of one of the intermediate elements or panels making up the end structure. Fig. 5 is a fragmentary sectional view illustrating a modification. Fig. 6 is an elevation of another form of the invention. Figs. 7 and 8, sectional views taken on lines 7—7 and 8—8 respectively, of Fig. 7; Fig. 9, a view in 50 perspective of one of the panels making up the end shown in the preceding three figures; Fig. 10, a sectional view similar to Fig. 8 showing a modification; Fig. 11, a view, in perspective, of one of the panels 55 employed in the modified construction

shown in Fig. 10; Fig. 12, an elevation of another embodiment of the invention; Figs. 13 and 14, sectional views taken on lines 13—13 and 14—14, respectively, of Fig. 12.

Like characters of reference designate like 60 parts in the several figures of the drawings.

The end structure shown in Figs. 1 to 4 inclusive is made up preferably of an upper panel 25 secured to the end plate 26 of the car, a lower panel 27 secured to the end sill 65 28 and a plurality of intermediate panels 29; the lower edges of the panels 25 and 29 being offset as shown at 30 and overlapping the panels respectively below them. Each of the several panels is formed with angularly disposed lateral flanges 31 secured in any suitable manner to the corner posts 32 of the car. Each panel is formed with an inturned corrugation 33 which preferably deepens toward the center of the panel so 70 that it provides a truss-like member extending across the concavity of the panel. Preferably the corrugations are pressed in to substantially the plane of the outer faces of the corner posts. That is, the depth of the 75 corrugations at the vertical section is substantially equal to the bulge of the panel at that point. This gives a maximum reinforcement without the waste of any space within the end framing of the car. The 80 structure may be further reinforced by forming the panels 29, and also if desired, the lower panel 27, with inturned flanges 34 on their upper edges which serve the same 85 function as the corrugations 33 forming truss or tie members resisting the deflection 90 of the panels under stress of cargo thrusts. The number of panels constituting the end might be increased or decreased as might be 95 found expedient.

In Fig. 5 the panels 27^a, 30^a are formed with flanges 34^a but are not corrugated.

In the construction shown in Figs. 6 to 9 inclusive, the end consists of four triangular panels 44, 45, 46, 47 preferably formed with 100 corrugations 48 and at their meeting edges with outstanding flanges 49 secured together by rivets 50, the flanges being widest at the center point of the end and tapering down to nothing at the corners. The panels 44, 46 105 are formed with angular flanges 51 for attachment to the corner posts 32. The upper panel 47 has a flat margin 52 in the plane of the panel which is secured by bolts 53 to the end plate 26. The corresponding mar- 110

ginal portion 54 of panel 45 is preferably bent inwardly and secured to the upper surface of the end sill 28 by bolts 55.

Figs. 10 and 11 show a modification of 5 the construction just described. The panels designated 44^a, 45^a, 46^a and 47^a are formed so that they are inclined toward the center point of the end, that is, toward the apex of the triangle in each case, and are provided 10 with inturned flanges 49^a at their meeting edges. In other respects the construction may be exactly the same as that shown in Figs. 6 to 9 inclusive.

The construction shown in Figs. 12 to 14 15 inclusive consists preferably of an upper sheet 65 and a lower sheet 66 formed with convex portions 67, 68 and united by a line of rivets 69. The center portion of the end which is of spherical curvature, is reinforced by providing the lower sheet 66 with an inturned flange 70.

I claim:

1. An end structure for railway cars comprising a plurality of rectangular metal 25 end sheets secured together, formed at their meeting edges with inturned angular flanges, and disposed so that the structure projects out farther at its vertical center line than at the sides.

2. An end structure for railway cars comprising a plurality of metal end sheets secured together, disposed so that they bulge out at the center and formed with interior flanges constituting trusses across the bulged 35 portion of the end.

3. An end structure for railway cars comprising a plurality of metal end sheets secured together, disposed so that said structure bulges out at the center and formed at 40 their meeting edges with inturned flanges.

4. An end structure for railway cars comprising a plurality of corrugated metal end sheets secured together, formed at their meeting edges with inturned angular flanges, and disposed so that the structure projects out farther at its vertical center line than 45 at the sides.

5. An end structure for railway cars comprising a plurality of corrugated metal end sheets secured together, disposed so that they bulge out at the center and formed with interior flanges constituting trusses across the bulged 50 portion of the end.

6. An end structure for railway cars com-

prising a plurality of corrugated metal end 55 sheets secured together, disposed so that they bulge out at the center and formed at their meeting edges with inturned flanges.

7. An end structure for railway cars comprising a plurality of metal end sheets 60 secured together, disposed so that they bulge out at the center and formed with inturned corrugations and with inturned flanges at their meeting edges.

8. An end structure for railway cars comprising a plurality of bowed panels extending 65 across the car from side to side with the edges of adjacent panels overlapping and formed with inturned flanges.

9. An end structure for railway cars comprising a plurality of bowed panels extending 70 across the car from side to side with the edges of adjacent panels overlapping and formed with inturned flanges and with inwardly pressed horizontal corrugations.

10. The combination with the end framing of a railway car, of a sheet metal end structure which is bulged outwardly from 75 said end framing and formed with reinforcing corrugations which extend from one corner post to the other and throughout their 80 length are pressed inwardly to substantially the plane of the outer surface of the end framing of the car.

11. The combination with the end framing of a railway car, of a sheet metal end structure which is bulged outwardly from 85 said end framing with a substantially uniform curvature from top to bottom of the end and formed with horizontal reinforcing 90 corrugations which extend from one corner post to the other and throughout their length are pressed inwardly to substantially the plane of the outer surface of the end framing 95 of the car.

12. A sheet metal end structure for railway cars which is convex and formed with one or more inturned corrugations, the depth of which at any section taken across the same is substantially the same as the amount 100 of convexity of the end structure at that place from the plane of the outer surface of the end framing of the car.

PERCIVAL H. TRUMAN.
